UNITED STATES PATENT OFFICE.

PETER G. LEHMAN, OF MISHAWAKA, INDIANA.

COLLAR-WRAPPING MACHINE.

1,224,858.

Specification of Letters Patent.

Patented May 1, 1917.

Application filed May 3, 1915. Serial No. 25,610.

To all whom it may concern:

Be it known that I, PETER G. LEHMAN, a citizen of the United States, residing at Mishawaka, in the county of St. Joseph 5 and State of Indiana, have invented certain new and useful Improvements in Collar-Wrapping Machines, of which the following is a specification.

The invention relates to a machine de-
10 signed primarily for the wrapping of collars wherein any predetermined number of collars may be properly applied to the wrapping roller and interwrapped and enveloped in a suitable wrapping of paper or other
15 material to provide a compact bundle or package, wherein the collars are held in a uniformly curved position to maintain their correct shape and prevent possibility of breaking while in the package.

20 The present improvement is designed particularly to provide for the expeditious handling of collars and material, the automatic severing of the material when the predetermined quantity has been used and the
25 simple and expeditious removal of the wrapped collars as a package from the machine, all parts being readily accessible for adjustment, removal or repair when desired.

Figure 1 is a front elevation partly broken
30 out, of the improved machine.

Fig. 2 is a side elevation of the same, the wrapping roller being shown in package removing position in dotted outline.

Fig. 3 is a plan of the machine.

35 Fig. 4 is a broken perspective showing the automatically adjustable cutter.

Fig. 5 is a perspective view of the wrapping roller.

In the accompanying drawings wherein
40 is shown the preferred embodiment of detail, the improved machine comprises a base 1 of suitable form to properly support the device, from which, near one edge, rises an upright 2, preferably in the form of a com-
45 paratively narrow and thin strap. Secured to the upright, near the upper end and project-
ing laterally therefrom, is a shaft 3 on which through the medium of the usual cone-supports 4, is designed to be arranged a
50 roller 5 of paper or other suitable material, the material being of sufficient width for the purpose desired.

Slidably mounted upon the upright 2 is
55 a cutter frame involving a slide element 6 having flanged or under-cut side walls to slidably embrace the edges of the upright 2,

whereby the slide has free telescopic move-
ment with relation to the upright. Projecting laterally from the upper end of the
slide frame is a cutter 7, comprising a com-
paratively narrow blade-like element, the
forward or cutting edge 8 of which is
slightly V-shaped in plan and appropriately
sharpened. As thus arranged it will be ob-
vious that through the telescopic or sliding
arrangement of the knife frame with the
upright the knife will rest upon the surface
of the roll of wrapping material at all times,
automatically accommodating itself to the
diminution of the roll as the material is
used. To one side edge of the knife frame,
as at 9, is secured an arm 10, on the upper
or free end of which is provided a sleeve-like
bearing 11. Rotatably mounted in the bearing
11 is a shaft projection 12 forming a
fixed part of what I term a wrapping roll
13. The shaft projection 12 of the roll is
slightly greater in length than that of the
bearing 11 and its outer end is of angular
form in cross-section as at 14, to receive an
appropriate opening in a crank operating
handle 15, whereby the roll is rotatable when
desired.

The roll proper comprises a hollow cylin-
drical body 16 formed immediately adjacent
the shaft projection 12 with an annular
roughened or knurled bearing surface 17.
The roller is formed with a longitudinally
extending slot 18 opening through the edge
thereof remote from the surface 17, and
extending approximately to said surface,
as clearly apparent from Fig. 5. The bearing
11 is of such length that when the roll
is in position therein the roughened surface
17 will bear upon the paper or other wrap-
ping material adjacent the edge thereof, as
clearly shown in Fig. 1, the said roughened
surface serving as a feed element to feed
the paper from the paper roll as the folding
roll is rotated. Secured to the sliding frame
95 adjacent one edge thereof and preferably
on the inner side is a paper or other material
guide 19 comprising preferably a strip of
wire or the like secured to the frame, pro-
jecting laterally across in front of the paper
roll and terminally extended upward in a
curved finger as at 20, which latter is posi-
tioned about mid-width the paper roll and
is curved into close proximity to and con-
centric with the surface of the wrapping
110 roll. The wrapping roll is preferably
slightly conical in shape, that is the free

end thereof is of slightly less diameter than the end carrying the roughened surface 17, for a purpose which will presently appear, and the arm 10 is also of a length to permit 5 the wrapping roll to rest by gravity immediately above the material of the paper roll on the side opposite the sliding frame to that on which the arm 10 is pivotally mounted, this disposition permitting the arm 10 10 to be turned upwardly toward the rear so as to move the wrapping roll a considerable distance from the proximate surface of the wrapping material or paper roll, as shown in dotted lines in Fig. 2.

15 In use, the collars to be wrapped are grouped together and their tabs at one end of the collars placed slightly within the slot or channel 18. The crank handle 15 is now rotated and the roughened surface 17 20 of the wrapping roll causes the paper, directed by the guide 19, to be fed upwardly around the wrapping roll, the end of the paper being held down by the operator until the same is gripped by the winding 25 of the collars and paper about the roll. The rotation of the wrapping roll rotates the collars about said roll and at the same time feeds the paper or other wrapping material between the respective rolls of the collars 30 and around the same. After a sufficient number of enveloping folds have been made, the wrapping roll as a whole is swung upwardly on the pivotal connection of the arm 10, which action causes the knife 7 35 to sever the paper, the V-shaped formation of the knife presenting a piercing point which initially pierces the paper, at about centrally of its width so that further upward movement of the paper causes the 40 knife to readily sever the same throughout its width. As the wrapping roll is of less length than the width of the paper it is obvious that there is presented immediately succeeding the operation described, a free 45 portion of paper beyond the free edge of the wrapping roll, which may be turned inwardly to seal the end of the package. The package and collars thus wrapped may be readily withdrawn from the wrapping 50 roll as the latter is slightly cone-shaped, after which the supports or relatively inner end of the package may be turned in to seal the same.

55 As presented the improved machine will readily wrap any number of collars, maintaining them in regular, even, rounded folds, and permit the ready sealing or closing of the package in the manner described. As the entire operative parts of the mechanism, 60 that is the wrapping roll, guide and cutter, are carried on a frame which automatically accommodates itself to the diameter of the roll of wrapping material, it will be obvious that the relative and proper position 65 of such parts with relation to the paper

will be at all times maintained, whereby the complete effectiveness of the device is insured.

What is claimed is:

1. A collar wrapping machine including a mounting for a paper roll, and a wrapping roll mounted for downward movement by gravity having operative contact with and supported against downward movement by the paper roll, whereby the wrapping roll will automatically adjust itself for operative relation with the paper roll as the latter is reduced in size by the use thereof. 70

2. A collar wrapping machine including a mounting for a paper roll, a wrapping roll, said wrapping roll being mounted on a swinging element to permit it to be positioned in contact with the paper roll or remain spaced therefrom. 80

3. A wrapping machine including a mounting for a paper roll, a wrapping roll, and means carried by the wrapping roll to feed the paper roll in the operation of the wrapping roll. 85

4. A collar wrapping machine including a paper roll supporting means and a wrapping roll, said wrapping roll having operative contact with the paper roll for rotating the latter in the operation of the wrapping roll. 90

5. A collar wrapping machine including a mounting for a paper roll, a wrapping roll, and means to guide the paper from the paper roll about the wrapping roll in the rotation of the latter. 95

6. A collar wrapping machine including a mounting for a paper roll, a wrapping roll mounted for rotative contact with the paper roll, and a guide to direct the paper about the wrapping roll in the rotation of the latter. 100

7. A collar wrapping machine including a mounting for a paper roll, a wrapping roll mounted for rotative contact with the paper roll, and a guide to direct the paper about the wrapping roll in the rotation of the latter, said guide and wrapping roll being mounted for compensative movement with respect to the paper roll. 110

8. A collar wrapping machine including a mounting for a paper roll, a wrapping roll, and an arm for supporting the wrapping roll for bodily movement with respect to the paper roll, said arm permitting the wrapping roll to gravitate in contact with the paper roll or to be swung to a position clear of said roll. 115

9. A collar wrapping machine including a frame, a paper roll supporting member mounted thereon, a slide frame mounted for movement on the first mentioned frame, and a wrapping roll carried by the slide frame for contacting with the paper roll. 125

10. A collar wrapping machine including a frame, a material roll supporting member 130

mounted thereon, an element having sliding engagement with the frame, an arm pivotally mounted in said element, and a wrapping roll rotatably mounted in the arm.

- 5 11. A collar wrapping machine including a frame, a material roll supporting member mounted thereon, an element having sliding engagement with the frame, an arm pivotally mounted in said element, and a wrapping roll rotatably mounted in the arm, said roll including a roughened portion to engage the material of the material roll.

- 10 12. In a collar wrapping machine, a main frame, an element slidably mounted thereon, a wrapping roll movably supported by the element, and a material guide arranged adjacent the wrapping roll and carried by the element.

- 15 13. A collar wrapping machine including a main frame, an element slidably mounted thereon, a wrapping roll, a material guide mounted on the element, and a movable connection between the wrapping roll and element to permit the roll to be moved into operative relation to the guide and material rolls or to a position spaced from said guide and material roll.

- 20 14. A collar wrapping machine including a main frame, a slide frame movably mounted thereon, a wrapping roll carried by and movable with the slide frame, and a knife carried by and movable with the slide frame.

- 25 15. A collar wrapping machine including a main frame, a slide frame movably mounted thereon, a wrapping roll carried by and movable with the slide frame, and a knife carried by and movable with the slide frame, said knife having a cutting edge including angularly related portions.

- 30 16. A collar wrapping machine including a material roll supporting frame, a slide frame movably mounted thereon, a wrapping roll carried by and movable with the

slide frame, and a knife carried by and movable with the slide frame, said slide frame maintaining contact between the knife and material of the material roll at all times.

35 17. A collar wrapping machine including a main frame, a slide frame movably mounted thereon, a wrapping roll carried by and movable with the slide frame, and a knife carried by and movable with the slide frame, said knife having a cutting edge including angularly related portions, the junction of the angularly related cutting edges being disposed approximately centrally of the knife.

40 18. A collar wrapping machine including a main frame, a slide frame movably mounted thereon, a wrapping roll carried by the slide frame, a material guide carried by the slide frame and a knife carried by the slide frame.

45 19. A collar wrapping machine including a main frame, a material roll supporting means mounted thereon, a wrapping roll, a material guide, a knife, and a single means for movably mounting the wrapping roll, guide and knife on the main frame to permit such parts to compensatingly adjust themselves with respect to the material roll, as the material is used therefrom.

50 20. A collar wrapping machine including a main frame, a slide frame movably mounted thereon, an arm pivotally mounted on the slide frame, a wrapping roll rotatably mounted at the free end of the arm, a knife rigidly connected to the slide frame and a material guide rigidly connected to the slide frame.

In testimony whereof I affix my signature in presence of two witnesses.
